UNITED STATES PATENT OFFICE.

JAMES M. MCHUGH, OF BOSTON, PENNSYLVANIA.

MINING-MACHINE.

SPECIFICATION forming part of Letters Patent No. 623,924, dated April 25, 1899.

Application filed December 7, 1897. Serial No. 661,089. (No model.)

To all whom it may concern:

Be it known that I, JAMES M. MCHUGH, a resident of Boston, in the county of Allegheny and State of Pennsylvania, have invented a new and useful Improvement in Mining-Machines; and I do hereby declare the following to be a full, clear, and exact description thereof.

My invention relates to mining-machines. In the accompanying drawings, Figure 1 is a plan view of the machine, showing the cutter-bar fully extended in position for the side cutting operation. Fig. 2 is a side view on a larger scale. Fig. 3 is a plan view showing the machine out of operation. Fig. 4 is a cross-section on the line 4 4, Fig. 3. Fig. 5 is a rear view of the frame. Fig. 6 is a front view. Fig. 7 is a view, partly in section, of the forward jack. Fig. 8 shows the jack used in the side cutting operation. Fig. 9 is a detail of the guide. Fig. 10 is a cross-section of same.

Like letters indicate like parts in each of the figures.

The frame of my machine consists of the two channel-bars *a*, connected together by means of the bar *a'* at the rear end and the bar *a''* at the front end thereof. These bars *a'* and *a''* have the turned-up portions *a³*, which are bolted to the outside of the channel-bars *a*. The cross-bar *a'* also has the depending braces *a⁴*, to which are bolted or otherwise secured the plate *a⁵*. Shoes *a⁶* are secured at their rear ends to the plate *a⁵* and at their forward ends to the underside of the channel-bars *a* for the purpose of forming supports for the rear end of the machine.

Secured to the connecting-bar *a''* and beneath the same is the support *a⁷*, having the two bent-up portions *a⁸* at each end thereof. The channel-bars *a*, as more clearly shown in Figs. 4 and 5, have the depending flanges *b* and the upturned flanges *b'*. Suspended between these two channel-bars *a*, with its flanges *b* resting upon the upturned flanges *b'* of the channel-bar, is the movable plate *c*. This movable plate *c* has the cutter-bar attached thereto and carries thereon certain mechanism, gearing, &c., through which the several motions of the machine are governed, the same being more fully hereinafter described.

Mounted upon the stationary frame of the machine and at about the center thereof is the motor *D*. The motor is secured to the table *d*, which is in turn securely bolted to the frame. The power-shaft *d'* from the motor extends forward to the front end of the machine, its forward end being journaled in the bearing *d²* at the upper end of the standard *d³*.

The shaft *d'* carries at its forward end the pinion *d⁴*, which meshes into the gear-wheel *d⁵* upon the counter-shaft *d⁶*, which extends the full length of the frame, its forward end being journaled in the bearing *d²* in the standard *d³* and its rear end being journaled in the bearing *d⁸*, secured to the bar *a'* of the frame. The standard *d³* is secured to the bar *a²*.

The counter-shaft *d⁶* has the keyway *d⁹* formed therein nearly the full length thereof.

A bevel-gear *c²* upon the vertical shaft *c³*, journaled in the bearing *c⁴* of the plate *c*, meshes into the bevel-pinion *c⁵* upon the shaft *d⁶*. The shaft *d⁶* passes through the bearing-block *c⁶*. The pinion *c⁵* is held in proper relation to the gear *c²* by means of the bracket *c⁷*, attached to the block *c⁶*. A key in the pinion *c⁵* extends into the keyway *d⁸* of shaft *d⁶*, said pinion revolving therewith and imparting motion to the gear *c²*, which, through the shaft *c³*, imparts motion to the chain-sprocket *c⁸* at the lower end of shaft *c³*, which in turn imparts motion to the cutter-chain *e*. The cutter-bar *f* is attached to the plate *c* and has the guide-bar *f'* attached thereto, which passes through the guide or slot *a⁹* in the support *a⁷* at the forward end of the frame.

As the machine is operated the plate *c*, carrying the cutter-bar *f*, is fed forward by certain mechanism which will be more fully hereinafter described. As the bar is thus moved forward the sprocket *c⁸* imparts motion to the chain *e* and the cutter *e'* thereon.

The frame *f* is formed straight upon the side *f²* for a purpose more fully hereinafter described. In the forward end of the frame are journaled the idle sprockets *f³* and at the rear of side *f²* is journaled the idle sprocket *f⁴*. These idle sprockets are for the purpose of guiding the sprocket-chain. A pinion *g* with a key therein is feathered upon the shaft *d⁶* and meshes into the gear-wheel *g'*, whose shaft is journaled in the bearing *g²*. At the other end of said shaft is the pinion *g³*, which

meshes into the gear-wheel g^4 upon the shaft g^5 , journaled in the bearing g^6 . Upon the shaft g^5 is also the worm g^7 , meshing into the worm-wheel h . The worm-wheel h is loosely mounted upon the shaft h' , which is journaled in the bearings h^2 upon the movable plate c . The outer ends of the shaft h' project into the channel-bars a . Upon these outer ends of said shaft h' are fixed the toothed wheels h^3 , which engage the pins i , inserted in the upper part of the bars a , and they are so arranged as to take the place of teeth for the reception of the teeth of the wheels h^3 for a purpose more fully hereinafter described. A worm k upon the shaft d^6 meshes into a worm-wheel k' upon the shaft h' . The worm-wheels h and k' are both loosely mounted upon the shaft h' and have the clutch-faces h^4 and k^2 , respectively, into which the clutch-faces l^1 and l^2 , respectively, of the clutch l are designed to engage. The clutch l is feathered upon the shaft h' and is operated by means of the lever l^3 .

As the motor is operated and the shaft d^6 revolved the cutter-bar is fed forward as follows: The clutch-face l^1 of clutch l is forced by lever l^3 into engagement with the clutch-face h^4 of worm-wheel h , and the shaft h' is revolved to move the cutter-frame forward through the train of gearing $g^1 g^2 g^3 g^4$, worm g^5 , and worm-wheel h upon shaft h' . The teeth of the toothed wheels h^3 upon ends of shaft h' engage the pins i and act therein to move the frame forward. When it is desired to reverse the feed, the clutch-face l^2 of clutch l is forced, by means of lever l^3 , into engagement with clutch-face k^2 on worm-wheel k' , and the motion of shaft h' is reversed and the cutter frame or bar recedes. The reverse motion is geared at a higher rate of speed than the forward feed. The bevel-pinion c^5 , pinion g , and worm k all have keys therein which engage the keyway d^8 upon shaft d^6 . As the plate c and the cutter-frame f are fed forward these pinions and worm are carried forward therewith, their keys always in engagement with the keyway d^8 . Permanently keyed to the shaft d^6 , at the rear end thereof, is the worm m . A worm-wheel m' upon the shaft m^2 meshes into the worm m , the shaft m^2 being journaled in the bearings m^3 . A clutch m^4 , operated by lever m^5 , is feathered upon the shaft m^2 for the purpose of engaging the clutch-face m^6 upon the worm-wheel m' , said worm-wheel being loosely mounted upon the shaft m^2 . A bevel-pinion n at end of shaft m^2 meshes into the bevel-gear n' upon shaft n^2 . The shaft n^2 is journaled in the bearings n^3 , situated one at the front end of frame and the other at rear end thereof. Pinions n^4 are keyed to shaft n^2 for a purpose more fully hereinafter described.

Standards o , being four in number, are bolted to the top of channel-bars a , two near the forward end and two near the rear end. These standards o have the eyes o' therein, through which the rack-bars p are adapted to

be passed. When said rack-bars are in place, the teeth of the pinions n^4 engage the teeth of the rack-bars p , said rack-bars being generally two in number. Slots p' are formed in the ends of rack-bars p for the reception of jacks R . The jacks R are more clearly shown in Fig. 8. The jacks R consist of the threaded bar r , having the pointed end r' , which engages the floor of the mine. This threaded bar r is passed through the slot p' of rack-bar p , and a nut r^2 upon the bar r directly beneath the rack-bar p allows the adjusting of the height of the rack-bar. A piece of tubing r^3 , with the upper pointed end r^4 for engaging the ceiling of the mine, fits upon the upper end of threaded bar r , and a nut r^5 upon bar r is for the purpose of raising the tubing r^3 . When the jacks are in place, the nuts r^2 are turned to raise the rack-bars to the desired height, and the tubings r^3 are raised by means of the nuts r^5 until the points r^4 and r' are firmly fixed into the ceiling and floor of the mine. When the jacks are thus firmly fixed, the rack-bars p are held firmly in position. By this construction the height of the machine above the floor may be readily changed. The rack-bars p may be readily elevated, thus raising the machine. It often happens that in making a cut the chain cutter will come in contact with hard rock which it cannot cut, and in order to avoid the rock it is necessary to elevate the machine to cut over it or lower it to cut under it, as the case may be. In this way the strain on the machine is relieved, and the cutting can continue without interruption.

Jacks S and S' are attached to the forward and rear ends of the frame, respectively, for the purpose of holding the frame rigid during the forward cutting operation. They consist of the frames s , having the downwardly-extending bifurcated straps s' . A threaded bar s^2 is fixed into the seat s^3 . A sleeve s^4 , with the upper pointed end s^5 , fits loosely over the threaded bar s^2 , and a nut s^6 upon the threaded bar s^2 may be operated to raise the sleeve s^4 and force the point s^5 into the wall of coal. The forward jack S' has one of the straps s' slightly longer than the other, so that when the bifurcated ends of said straps engage the studs t on the frame the sleeve s^4 will be slightly pitched to one side, so as to hold the feed from following a diagonal line due to the direction of movement of the cutter-chain. A shaft u is journaled at its rear end to the plate c and at its forward end to the cutter-frame f . A seat u' is formed near the forward end of the shaft for the reception of the guide-tool u^2 . A plate u^3 is bolted to the enlargement u^4 , which holds the tool u^2 in its seat. The tool u^2 has the sharpened edges u^5 , as more clearly shown in Fig. 10. These sharpened edges enter the upper and lower faces of the cut as it is being formed and aid to guide the feed in a straight forward line. At the rear end of the shaft u is formed the angular enlargement u^6 , which is engaged by

the keeper u^7 , pivoted to the plate c at u^8 . After the forward cut has been completed the keeper u^7 is swung upon its pivot u^8 to remove it from the enlargement u^6 , when a wrench or tool may be applied thereto to turn the shaft u and tool u^2 to the position shown in Fig. 1.

At or near the rear end of the frame is the plate v , carrying the rollers v' , which are V-shaped on their circumference. The ends of the plate v are slotted to slide upon the perpendicular rods w , fixed in the shoes a^6 . A nut v^2 is bolted to the under side of plate v^3 , said plate being secured to under side of frame. A threaded bolt y passes through said nut and corresponding opening in the plate v^3 , the lower end of bolt y entering in the seat y' upon the upper face of plate v . The bolt y has the head y^2 , by which said bolt may be turned to raise or lower the plate v . These rollers when lowered during the side cutting operation relieve the rack-bars p from a part of the weight of the machine. The rack-bars p are made of such a length that they may be put in place while the machine is in position for operation. It is therefore necessary to make them shorter than the width of the room, and therefore it will be necessary during the side cutting operation to move the rack-bars and again adjust them before finishing the cut. During this movement the rollers v' are lowered, so as to sustain the full weight of the rear end of machine, and if the support a^7 is not resting firmly upon the floor at that time it will be necessary to block it up.

The operation of my improved machine is as follows: The machine is first placed in position, with the forward end up close to the wall of coal. The machine previous to starting operations will be as shown in plan view, Fig. 3. It is usual in mining to start the cutting at the left-hand side of the room facing to wall of coal to be cut. When my machine has been thus placed, the jacks S and S' are put into position and the frame held rigidly thereby. The clutch-face l' of clutch l is thrown, by means of lever l^3 , into engagement with the clutch-face h^4 on worm-wheel h . Power is then applied to the motor and the shaft d^6 revolved, and the cutter-chain e is moved through the bevel-gearing c^2 and c^5 and the sprocket-wheel c^8 . The tools e' upon chain e act to cut the coal, and the cutter-frame is fed forward by means of the train of gearing before mentioned, the toothed wheels h^3 meshing into the pins i . The guide u^2 is held in the position shown in Figs. 2 and 3 by means of the keeper u^7 during the forward cutting to aid in keeping the cutter-bar in line. The edges of the tool cut a groove in the top and bottom faces of the cut as the cutter-frame is fed forward. When the forward cutting has been completed, the lever l^3 is operated to throw the clutch l out of engagement either by hand or automatically by means of a stop placed in proper position upon the frame. The feed being thrown out

of gear, the forward movement of the cutter-frame is checked. The current or power is then cut off. The keeper u^7 is swung out of engagement with the angular enlargement u^6 of the shaft u and a wrench or other tool applied to turn the guide or tool u^2 flat, as shown in Fig. 1. The jacks S and S' are removed and the rack-bars p thrust through the eyes o' in standards o . The jacks R are put in place in the slots p' of rack-bars p and the nuts r^5 operated to force the points r' and r^4 firmly into the floor and ceiling, respectively, of the room. The nut r^2 is then operated to relieve the weight of the machine from the floor. By operating the bolt y the wheels or rollers v' are forced down until they come in contact with the floor of the mine. By operating the lever m^5 the clutch m^4 is thrown into engagement with the clutch-face m^6 on worm-wheel m' , and through the gearing before mentioned the pinions n^4 are revolved, and their teeth engaging the teeth of the rack-bars p operate to feed the machine crosswise in the direction of arrow, Fig. 2. The machine hangs by means of the standards o from the rack-bars p . As the machine is thus fed sidewise and the cutter-chain is operated a side cut is made in the coal, and the whole cut is made in two operations.

In the usual type of machines now in general use it is necessary after the first forward cut is made to run the cutter-frame back, move the machine sidewise a distance equal to the width of cut made, and proceed in a similar manner until the cut has been made the full width of the room.

In my improved machine the cutting operation first starts forward in one corner of the room, and then after the forward cut has been completed the machine is operated to perform a side cut, as previously described, to finish the cut across the width of the room. When the side cut has been completed, the lever m^5 is operated to throw the clutch m^4 out of engagement, thus stopping the feed. The lever l^3 is then operated to throw the clutch-face l^2 of clutch l into engagement with the clutch-face k^2 of worm-wheel k' . The reverse-gear is then operated to draw the cutter-frame f back to the position shown in Figs. 2 and 3. I have made the side f^2 of the cutter-frame f on a line parallel with the sides a of the main frame, so that the cutter-bar may be withdrawn more readily and to make the finished cut square, it being obvious that if said side f^2 of the cutter-bar were on a diagonal similar to the other side the cutters would have to cut away the bevel as said cutter-bar recedes. This would be impractical where the reverse feed was made to operate so much quicker than the forward feed.

I do not wish to limit myself in any sense to the mechanism shown and described, as that may be varied without affecting the scope of my invention.

What I claim as my invention, and desire to secure by Letters Patent, is—

1. In a mining-machine, the combination of a suitable frame, cutting mechanism on said frame, means for advancing said cutting mechanism longitudinally into the coal and for moving said frame transversely of the cut, a rocking bar on said frame, a cutter-guide on said bar adapted to form a longitudinal groove in the coal, and means for locking said bar in position, substantially as set forth.
2. In a mining-machine, the combination of a suitable frame, cutting mechanism on said frame, means for advancing said cutting mechanism longitudinally into the coal and for moving said frame transversely of the cut, a rocking bar on said frame, a cutter-guide on said bar adapted to form a longitudinal groove in the coal, and a latch adapted to engage said bar and lock it in position, substantially as set forth.
3. In a mining-machine, the combination of a suitable frame, cutting mechanism on said frame, means for advancing said cutting mechanism longitudinally into the coal and

for moving said frame transversely of the cut, a rocking bar on said frame having an angular portion thereon, a cutter-guide on said bar adapted to form a longitudinal groove in the coal, and a keeper adapted to engage said angular portion, substantially as set forth.

4. In a mining-machine, the combination of a main frame having channel-bars extending longitudinally thereof, the open faces of said channel-bars facing each other, downwardly-projecting flanges on said bars, pins passing through said bars and flanges forming racks thereon, a movable frame, cutting mechanism carried by said frame, a shaft on said frame, pinions on said shaft engaging said racks, and mechanism for rotating said shaft, substantially as set forth.

In testimony whereof I, the said JAMES M. McHUGH, have hereunto set my hand.

JAMES M. McHUGH.
